SHOE

William F. Cairns, North Haven, Conn., assignor
to United States Rubber Company, New York,
N. Y., a corporation of New Jersey

Application August 15, 1941, Serial No. 406,964

3 Claims. (Cl. 36—45)

This invention relates to shoes of the laced type, and more particularly to canvas or other types of lace shoes designed for athletic use.

Many players of tennis and other athletic games prefer a type of shoe that laces well down to the toe, since this permits better adjustment of the shoe to the foot and provides a closer fitting shoe that affords better support. The greatest objection to this type of shoe is that it normally introduces one or more seams in the toe or fore part of the shoe which may cause discomfort and produce blisters upon the foot.

Various constructions have been proposed heretofore to provide a shoe that laces well down to the toe and at the same time form the seam or seams in the toe area so that it will not chafe the foot, but these prior constructions have not entirely overcome the difficulty caused by a seam in this area.

The present invention relates to what is commonly known as the lace-to-toe type of shoe, and contemplates a novel construction that avoids the necessity of providing seams in the toe portion of the shoe where they are likely to cause discomfort or blister the foot.

A primary feature of the present invention resides in what is herein called an over-lay having the shoe tongue formed integral therewith, and which over-lay is adapted to cover at least part of the vamp at the outside of the shoe, and be secured in place without the formation of the above-mentioned objectionable seam at the inside of the shoe.

This over-lay construction has a further important advantage in that by extending it back along each side of the shoe along the toes, a reinforcement is provided for that portion of the shoe which receives the most severe wear. Furthermore by providing this over-lay at the fore part of the shoe with the tongue integral therewith, the shoe is given a novel and pleasing appearance.

In carrying out the present invention it is desirable to form the vamp and two quarters of one integral piece of fabric and thereby avoid the use of seams to join the vamp and quarters. Such seams would disturb the smooth interior construction of the shoe, which is an important feature of the present invention.

The above and other features of the present invention will be further understood from the following description when read in connection with the accompanying drawing illustrating one good practical embodiment of the invention.

In the drawing:

Fig. 1 is a top plan view of a shoe embodying the features of the present invention.

Fig. 2 is a plan view of the inside of the complete upper for the shoe of Fig. 1.

Fig. 3 is a plan view of the cut-out integral vamp and quarter piece forming the outer material for the shoe upper of Fig. 1 and having the lining secured thereto.

Fig. 4 is a plan view of the over-lay and integral tongue forming important parts of the present invention; and

Fig. 5 is a plan view of an eyelet stay of usual construction.

The invention is described and illustrated herein in reference to a canvas shoe of the type commonly known as a lace-to-toe construction and is applicable either to high or low shoes of the lace type.

The shoe shown in Fig. 1 is a low canvas shoe 20 the sole 10 of which may be of the usual or any preferred construction, and the upper of the shoe is formed largely of the integrally-cut outer fabric material 11 of Fig. 3, comprising the quarters 12 and 13 and vamp or fore part 14. The material 11 it will be noted is provided with a deep slot 15 which is closed at its lower end in the toe area of the shoe as indicated by 16. The shoe upper, as will be apparent from Fig. 2, is provided throughout with a lining 17 which preferably 30 constitutes one integral piece of fabric the shape of which is practically the same as that of the outer fabric 11 shown in Fig. 3. The lining 17 and outer fabric 11 are preferably adhesively secured together.

The quarters 12 and 13 are secured together at the rear of the shoe by the vertical seam 18, and the rear portion of the shoe upper is provided with the usual counter 19. An eyelet stay 20 is secured as usual to each side of the slot 15 to receive the eyelets 21 adapted to receive the shoe lacing. The upper edge of the shoe and the edges of the slot 15 are preferably provided with the usual binding 22 as shown to give these parts a finished edge.

The shoe construction so far designated by reference characters is, for the most part, of well known construction except for the formation of the end portion 16 of the slot 15, which end portion it will be noted is of increased width, for a purpose to be described.

In accordance with the present invention the upper shown in Fig. 2 has secured to the outer face of the fore portion thereof the over-lay of Fig. 4 comprising the front portion 23, side portions 24 and 25 and tongue 26 all integrally con-

nected. The shape of this over-lay may be varied extensively depending upon whether or not it is desired to employ the same to reinforce a small or large area of the fore part of the shoe. In the construction shown the side portions 24 and 25 are so constructed that they will extend backwardly at each side of the shoe for nearly half the length of the shoe to thereby reinforce the front side portions of the shoe where the wear is most severe.

The upper shown in Fig. 2 may be attached to the sole 10 in the usual manner, and is provided with the usual foxing 21.

The tongue 26 of the shoe and the edges of the portions 24 and 25 of the over-lay lying near the tongue are preferably provided with the binding 28, and the portion of the over-lay provided with the binding 28 is sewed to the outer fabric 11 of the shoe upper as at 29. The outer edge portion of the over-lay is substantially co-extensive with the front portion of the shoe upper and is secured to the sole with the edge of the shoe upper which it overlies.

The construction of the over-lay of Fig. 4 is such that it covers and conceals the lower closed end portion 16 of the slot 15, and the tongue 26 extends inwardly through the wide portion of the slot formed adjacent its end 16 to lie under the rows of eyelets 21 as shown in Fig. 1.

It will be apparent from the foregoing that a shoe constructed in accordance with the present invention is practically free from joining seams which would be likely to irritate or chafe the foot, even when the shoe is laced tightly upon the foot to increase the snugness of its fit. It will also be seen that by providing the over-lay herein described a reinforcement is provided for those portions of the shoe upper which receive the most severe wear, and it will be apparent that the shoe is given a novel and pleasing appearance. Furthermore the shoe construction herein disclosed is simple and inexpensive to make.

Having thus described by invention what I desire to protect by Letters Patent is:

1. In a lace-to-toe type of shoe, a sole, an upper secured thereto and comprising a vamp

and two quarters, said upper having a deep central foot-receiving slot that extends into and terminates in the toe area of the shoe, such closed end of said slot being enlarged and provided with a curved edge merging into the sides of said slot and free from sharp turns, and an over-lay forming a cover for at least part of the vamp at the outside of the shoe and having an integral tongue that passes inwardly through said enlarged end of said slot.

2. In a canvas lace shoe, a sole, an upper secured thereto and comprising a one-piece vamp and quarters adapted to provide a smooth inner surface, said upper having a front, central foot-receiving slot having edges adapted to be drawn towards each other with a shoe lace, said slot terminating in the toe area of the shoe, such closed end of said slot being enlarged and provided with a curved edge merging into the sides of said slot and free from sharp turns, the edges of said slot being covered with binding tape which extends along said curved end edge to reinforce same, and an over-lay forming a cover for at least part of the vamp at the outside of the shoe and having an integral tongue adapted to be extended through said enlarged end of said slot from the outside of the shoe to the inside.

3. In a canvas lace-to-toe type of shoe, a sole, an upper secured thereto and comprising a vamp and two quarters, said upper having a deep foot-receiving slot that extends into the toe area of the shoe and is closed at its lower end, said slot being bound with tape and enlarged at its closed end by the removal of material, said closed end of said slot having a curved edge merging into the sides of said slot and free from sharp turns throughout which facilitates the application of said binding tape to said edge, an over-lay provided with an integral tongue and forming a cover for at least part of the vamp at the outside of the shoe, and said tongue being arranged to conceal the closed end of said slot and to pass inwardly through said enlarged end of said slot.

WILLIAM F. CAIRNS.
